US00D951971S

(12) **United States Design Patent** (10) **Patent No.:** **US D951,971 S**
Dieken et al. (45) **Date of Patent:** **** May 17, 2022**

(54) **DISPLAY SCREEN OR PORTION THEREOF WITH A GRAPHICAL USER INTERFACE**

(71) Applicant: **INSPIRE MEDICAL SYSTEMS, INC.**, Golden Valley, MN (US)

(72) Inventors: **David Dieken**, Minneapolis, MN (US); **Maria Isabel Ancona**, Boston, MA (US); **John Rondoni**, Plymouth, MN (US)

(73) Assignee: **INSPIRE MEDICAL SYSTEMS, INC.**, Golden Valley, MN (US)

(**) Term: **15 Years**

(21) Appl. No.: **29/797,405**

(22) Filed: **Jun. 30, 2021**

Related U.S. Application Data

(63) Continuation of application No. 29/724,942, filed on Feb. 20, 2020, now Pat. No. Des. 924,261, which is a continuation of application No. 29/670,042, filed on Nov. 13, 2018, now Pat. No. Des. 877,166, which is a continuation of application No. 29/617,338, filed on Sep. 13, 2017, now Pat. No. Des. 833,461.

(57) **CLAIM**

We claim the ornamental design for a display screen or portion thereof with a graphical user interface, as shown and described.

DESCRIPTION

The FIGURE is a front view of a display screen or portion thereof with a graphical user interface showing our new design.

The outermost broken lines show a display screen or portion thereof and form no part of the claimed design. The remaining broken lines show elements of the graphical user interface that form no part of the claimed design.

1 Claim, 1 Drawing Sheet
